UNITED STATES PATENT OFFICE.

AMOS FISHER, OF CRESTLINE, OHIO.

HEATING APPARATUS.

SPECIFICATION forming part of Letters Patent No. 681,019, dated August 20, 1901.

Application filed February 9, 1899. Serial No. 705,075. (No model.)

To all whom it may concern:

Be it known that I, AMOS FISHER, a citizen of the United States, and a resident of the city of Crestline, in the county of Crawford, 5 in the State of Ohio, have invented certain new and useful Improvements in Heating Apparatus, of which the following is a complete and correct description.

The invention relates particularly to an apparatus for heating dwellings and other structures by supplying heated air to the various apartments thereof, the air being warmed in a chamber which incloses the furnace proper of the apparatus and then conducted through suitable conduits to such apartments. Heaters of this character are ordinarily located in a cellar or in a basement; but under some circumstances they are placed wholly outside the structure which is to be warmed.

20 The invention consists in the provision in an apparatus of the character above indicated of various novel elements or combinations of elements, as will be hereinafter particularly described and then specifically pointed out in 25 the claims.

In the accompanying drawings, which constitute a part of this specification, Figure 1 represents a central vertical section in a plane extending through the inlet and outlet openings of the air-chamber, which encircles the fuel-chamber of the apparatus. Fig. 2 is a vertical central section in a plane essentially at a right angle with that of Fig. 1. Fig. 3 is a horizontal section as in the line *y* *y* of Fig. 1. Fig. 4 is a horizontal section taken in the line *x* *x* of Fig. 1. Fig. 5 is a top plan view showing the reservoir-cover, the annular steam or hot-water chamber, the cylindrical upper section of the body of the combustion-chamber resting upon the reservoir-cover, and the series of arches or radiating loops which rest upon and are connected with the annular water and steam chamber. Fig. 6 represents a plan of the annular water or 45 steam chamber, the surmounting radiating arches or loops having been detached.

From the center of the broad circular base-plate *a* of the furnace or heating apparatus *A* rises the circular ash-pit or ash-chamber *a'*, within the upper extremity of which rests the grate *ag* and upon which by its bottom groove *a''* is received the fire-pot section

a''. The fire-pot section *a''*, as will be observed, incloses by its outer wall *a''* and by its inner wall or fire-pot proper, *a''*, an air-warming chamber *a''*, which at one side has a projecting air-inlet passage or air-trunk *a''* and at its opposite side a warm-air-discharging opening *a''*. The upper portion of this fire-pot section *a''* consists of a broad 55 outwardly-overhanging plate *a''*, which is composed of steel and which is encircled by an attached ring *r*, which has an upper and a lower recess or shoulder *r's* and which in its upper surface has a shallow depression or recess *a''* to receive the correspondingly-flattened bottom extremity of the water section or reservoir *a''*, which, as will be noted, is circular in its lower portion below the fuel-opening *af* and of horseshoe form in its upper 60 portion, the water supplied through the feed-pipe *a''* being contained between the outer shell or cylindrical wall *a''* and the inner cylindrical wall *a''*. Upon the water section or reservoir *a''* is received the ring *a''*, which 65 in its bottom surface has inner and outer concentric grooves *a''* and *a''* to receive, respectively, the wall *a''* and the wall *a''* of the water-section and which is provided also with an upper or top groove *a''* to receive the 70 vertical annular or cylindrical combustion-chamber section *a''*, which is preferably plain and imperforate, as shown. Resting upon the covering-ring *a''* and encircling its superposed cylindrical section *a''*, is the horizontally-arranged tubular steam-section *a''*, 75 which has oppositely-placed pipes *ap* *ap*, which extend downwardly through openings in the covering-ring *a''* into the water section or reservoir *a''*. From the upper portion 80 of the encircling steam-section *a''* rise the arched steam-pipes or radiating-arches *ar*, in any suitable or convenient number. Upon the cylindrical combustion-chamber section *a''* rests by its bottom groove *gr* the covering-section or dome-section *a''*, 85 which is upwardly rounded, as shown, and which in its central portion is composed of the thick heat-absorbing casting or inverted basin-like cap *c*, which near its periphery has 90 the bottom groove *gr*, already referred to. This section has an attached depending rod *a''* for an inverted cone or deflector *ad*, which 95 is in line with and below the smoke-exit as 100

of the cone, and upon its exterior surface it has a series of outwardly-projecting arms a^{29} , which at their outer extremities receive a supporting-ring r^2 for attachment of a section of the hot-air chamber or heat-reservoir to be further described.

From an opening in the upper portion of the encircling steam-section a^{26} a steam-escape pipe ep extends first directly upward, 10 then horizontally outward through the body of the air-casing, and then upward to a suitable distance, where at its terminal point it is provided with a safety-valve sv . The smoke-exit pipe a^{31} is composed of two vertical sections and four horizontal sections—namely, 15 the primary vertical section a^{32} , rising from the exit-opening as ; the horizontal section a^{33} , extending outward to a point beyond the plane of the furnace proper; the vertical section a^{34} , extending downward to a point below the rounded portion of the dome-section, 20 and the three-part horizontal section a^{35} , consisting of the two plain sections s and s^2 and an intermediate damper-section or check-draft and clearing-section a^{36} .

As here shown, the air-casing A^2 of the heating apparatus is composed of three horizontal sheet-metal sections h , h^2 , and h^3 . The lowermost section h is fitted to the circular 30 base-plate a and to the ring r . The topmost or dome section h^3 covers the dome, and by its lower extremity is fitted to the uppermost ring r^2 . The intermediate casing-section h^2 encircles the coincident water section or reservoir a^{15} and is fitted to the rings r and r^2 . The intermediate casing-section h^2 and the lowermost casing-section h are at their ends provided with securing-lugs sl to receive fastening-bolts fb , Figs. 3 and 4, while the 40 upper or dome section h^3 of the casing is adapted to be lifted bodily upward. The horizontally-curving metallic front A^3 , which has ash-pit opening covered by a door d , draft-opening covered by door d^2 , and fuel-supply opening provided with door d^3 , is secured to the front of the casing by means of suitable screws. From the upper extremity or steam-space of the water section or reservoir steam-pipes ap extend through the covering 45 plate or ring a^{21} into the tubular steam ring or section a^{26} , from which it finds its way in part into the series of arched steam sections or loops ar , in part into a pipe which extends to a radiator in an upper story, and in part 50 into a pipe sp , which extends first upwardly within the hot-air casing, then horizontally outward within a supplemental hot-air pipe hap , and thence directly upward within a continuation of the same hot-air pipe, at the 55 extremity of which it is formed into a steam-coil sc at a point coincident with the opening of a wall-register or of a floor-register fr .

The grate ag , before referred to, is provided with a central opening or clearing-aperture which is closable by means of a 60 slide-plate or grated section which rests in

marginal ways of the grate and is operated by a suitable handle or rod. The outer periphery of the grate, which is circular, as best seen in Fig. 4, rests upon antifriction 70 wheels or rollers ro , which in turn are supported upon pivot pins or bearings which are received in the body of the bed-plate bp of the fire-pot section a^3 .

A heating apparatus thus constructed 75 combines various important advantages. By reason of the provision of the air-passage directly encircling the fuel-chamber or fire-pot and receiving air at one side and discharging it at the opposite side thereof the 80 currents of air are subjected to a high temperature through their contact with the highly-heated surface of the fire-pot until the moment of their discharge into the encircling air-chamber. Through the provision 85 of the water chamber or reservoir directly surmounting the fuel-chamber or fire-pot the inner face of such chamber or section is exposed to the direct action of the volatile products of combustion as they rise from the 90 incandescent fuel, causing quick ebullition of the contents of the section and rapid production and discharge of steam into the steam-section above. Through the provision of the steam-section, acting in conjunction with the 95 water-section and with the loops or steam-arches upon such steam-section, an extensive heat-radiating surface is afforded, still further elevating the temperature of the air within the hot-air chamber. Because of the 100 provision of the inverted cone in the upper portion of the combustion-chamber directly below and in connection with the exit-opening at the upper extremity of the dome or covering-section the products of combustion 105 as they rise are deflected and spread outwardly, thereby imparting a high temperature to the heavy mass of metal of which the main portion of the dome is composed, and thus providing, as it were, a reservoir of heat 110 for warming the space within the air-chamber. Through the peculiar construction and arrangement of the smoke-discharging pipe its contents dive low before escape is possible. The currents are thus retarded in their 115 flow, their contained caloric is in large degree imparted to the pipe for radiation therefrom, and a damper for such pipe is in most cases not required. By reason of the provision of the check-draft and clearing-section 120 in the exposed portion of the smoke-discharging pipe outside the hot-air casing it is made easy to regulate the movement of the smoke-currents and also to readily remove from the section and from contiguous portions of the 125 discharging-pipe accumulations of soot and other substances resulting from combustion without removing any portion of the casing of the hot-air chamber. Through the construction of the hot-air casing in superposed horizontal sections each section is made independently removable, thereby affording 130

ready access to any portion of the hot-air chamber without necessity for removing such casing as a whole.

5 The purpose, the construction, and the operation of the heating apparatus having been thus fully described, what is claimed is—

1. In a heating apparatus, the combination of a fuel-chamber section; a water-section which is mounted upon the fuel-chamber section; a covering-ring which rests upon the water-section, and which is provided with downwardly-extending steam-receiving pipes; and a steam-section which rests upon the covering-ring of the water-section, and 10 which, by means of the steam-receiving pipes, has communication with such water-section; substantially as shown and described.

2. In an air-heating apparatus, a fuel-chamber section which at its upper extremity has 15 an outwardly-extending peripheral projection; a water-section which rests upon such peripheral projection; a solid covering-ring which is grooved above and below, and which has upwardly and downwardly projecting 20 steam-conducting pipes; and the described annular, transversely-circular, steam chamber or conduit which is provided with a series of superposed arch-like steam-loops or radiating branches, and which rests upon the solid 25 covering-ring of the water-section; in combination; as set forth.

3. In an air-heating apparatus, the combination of a fire-pot or fuel-chamber section which has a broad, overhanging, peripheral 30 projection; a water-section which rests upon a peripheral projection of the fuel-chamber section; a covering-ring which by its bottom grooves is received upon the inner and the outer wall of the water-section; an annular 35 combustion-chamber section which rests in a groove in the covering-ring; and a horizontally-arranged steam chamber or passage which also rests upon the covering-ring, and 40 which is in communication with the water-section.

4. The fire-pot or fuel-chamber section, resting upon the ash-pit section, and having the horizontally-extending air-warming chamber 45 a^7 , and the ring or plate a^{12} , provided with top 50 recess a^{14} ; the water-section a^{15} , resting in the recess a^{14} , of the covering and supporting plate a^{12} , and having the described supply-pipe a^{18} ; the grooved covering-ring a^{21} , having the vertically-placed steam-pipes ap , and 55 supporting the cylinder a^{25} , and the encir-

cling steam-distributing chamber or passage a^{26} , which also is mounted upon the ring a^{21} ; in combination.

5. In a heating apparatus, the combination with the combustion-chamber; of a surmounting dome or cap which is composed of a thick, metallic, hollowed and rounded cone; and a vertically-adjustable deflector which is supported, centrally, within the upper portion of the combustion-chamber, and is of inverted 60 conical form, to adapt it to deflect and to direct laterally outward and upward, the ascending currents of smoke and other volatile products of combustion.

6. In a heating apparatus, the combination 70 with the combustion-chamber; of a surmounting dome or cap which is of rounded conical form, and of a thickness several times greater than that of the contiguous body of the combustion-chamber, and which at its top is provided with a central smoke-discharge opening; and a deflector, of inverted conical form, supported centrally within the combustion-chamber, at a short distance below the escape 75 or smoke-discharge opening, and provided upon its supporting-rod with means of adjustability, up or down; substantially as described and shown.

7. In a heating apparatus, the combination 80 of the water-section a^{15} ; the covering-ring a^{21} ; the steam-chamber a^{26} , resting upon the covering-ring; the steam-pipes ap , mounted in the covering-ring, and projecting into the water-section, and into the steam-chamber; and the series of steam loops or arches ar , 85 resting at each end upon the steam-chamber; substantially as and for the purposes specified.

8. The combination with the water-section, resting upon the fuel-chamber section; of the 90 covering-ring a^{21} , carrying the perpendicular steam-pipes ap ; the combustion-chamber and dome sections a^{25} and a^{27} ; and the steam-section a^{26} , encircling the combustion-chamber section, resting upon the covering-ring, 95 and having the series of superposed steam-loops or radiating-arches ar ; substantially as shown and described.

In testimony whereof I have, on this 7th day of November, 1898, affixed my signature 100 in the presence of two subscribing witnesses.

AMOS FISHER.
